ATTORNEY.

UNITED STATES PATENT OFFICE.

CHARLES H. TIERNEY, OF PAWTUCKET, RHODE ISLAND.

CRAPE-HOLDER.

997,519.

Specification of Letters Patent. Patented July 11, 1911.

Application filed June 15, 1910. Serial No. 566,903.

To all whom it may concern:

Be it known that I, CHARLES H. TIERNEY, a citizen of the United States, residing at Pawtucket, in the county of Providence and 5 State of Rhode Island, have invented certain new and useful Improvements in Crape-Holders, of which the following is a specification.

My invention relates to a device adapted 10 for suspending crape, ribbons, or other mourning articles from a door or jamb, and its principal objects are to avoid excessive defacement of wood work, to firmly engage the fabric without injury to the texture thereof, to afford an ornamental effect, 15 and to effect these ends by a simple, strong, and inexpensive structure.

To the above ends essentially my invention consists in the novel construction and 20 combination of parts hereinafter set forth and constituting the subject matter of the appended claim.

In the accompanying drawings which 25 form a part of this specification and in which like characters of reference indicate like parts throughout the views, Figures 1, 2, and 3, are rear, end and plan views respectively of my novel crape holder, Fig. 4, a front elevation of the same engaging a fabric, 30 Fig. 5, a section on line $x-x$ of Fig. 4, and Fig. 6, a section on line $y-y$ of Fig. 1.

My novel crape holder comprises a plate or body A preferably of metal and in the present instance provided with a central 35 opening, a . If desired the face of the plate or frame A may be embossed or otherwise ornamented.

Soldered or otherwise fixed to the upper

portion of the back of the plate are two 40 sockets B in horizontal alinement with each other in which are fixed pins C, preferably held in position by swaging the sockets as at b around the pins.

Near the vertical edges of the plate, upon 45 its back and in horizontal alinement with each other, are fixed a catch D, and a pivot pin E of any usual construction. On the latter is pivotally mounted a pin F whose end is adapted to engage in the catch D. The members D and E are in vertical alinement with the pin members C, but the latter extend a considerably greater distance from 50 the plane of the plate A than do the members D and E.

In Figs. 4 and 5 is shown my holder 55 engaging a streamer of crape H which is embraced between the plate A and the pin F. The plate A and its attached materials are rigidly and securely held in position by the points of the pins C which are manually 60 pressed into the door or jamb J.

What I claim is,—

In a crape holder, a flat plate having an opening therein and provided with pins projecting from the rear face thereof adjacent 65 the upper edge and a catch and pivot pin on the same face adjacent the opposite edge of the plate, the pins extending beyond the planes of the pivot pin and catch.

In testimony whereof I have affixed my 70 signature in presence of two witnesses.

CHARLES H. TIERNEY.
